UNITED STATES PATENT OFFICE

MILo SHUTT, OF ALLIANCE, OHIO, ASSIGNOR TO THE ALLIANCE MACHINE COMPANY,
OF ALLIANCE, OHIO, A CORPORATION OF OHIO

CAR HOLDING MECHANISM

Original application filed December 5, 1928, Serial No. 323,983. Divided and this application filed September 18, 1929, Serial No. 393,382.

My invention relates to car holding mechanisms, and more particularly to car clamping mechanisms for car dumpers. In my co-pending application, Serial No. 323,983, I have described and shown a mechanism for transferring coal, ore and the like from a car to a receiver, without excessive breakage of the material being transferred. The present invention particularly relates to car clamping mechanisms suitable for use with car dumpers of the same general character.

In the handling of cars moving onto a cradle, it has heretofore been necessary to clamp the cars firmly against the cradle before the cars are rotated about their longitudinal axes. Where the cars are clamped firmly to the cradle before rotative movement of the cradle begins, considerable time is lost in placing the clamps after the car is at rest on the cradle.

I provide means for automatically clamping a car in the cradle as the cradle rotates and automatically release the car as the cradle returns to its initial position. This construction eliminates the loss of time heretofore experienced for placing the clamps in position before rotation of the cradle takes place.

The accompanying drawings illustrate the present preferred embodiment of the invention, in which

Figure 1 is an end view of a car dumper in its initial position,

Figure 2 is a similar view of the car dumper in an intermediate position,

Figure 3 is a view showing in full lines the position of the car dumper when in position to discharge material into a receiver and showing in dotted lines a portion of the car dumper in its initial position,

Figure 4 is an edge view of the discharge spout,

Figure 5 is a longitudinal sectional plan view of the car dumper taken substantially along the section line V—V of Figure 1, and

Figure 6 is a diagrammatic view showing the movement of the discharge spout during a discharging operation.

Referring to the drawings, a car cradle 2 is supported along one side by brackets 4 engaging pins 5 which extend through sta-

tionary pillow blocks 6. The pillow blocks are supported by a foundation 7 of structural shapes and supporting masonry of any suitable form. The brackets 4 are preferably mounted near the ends of the cradle. The shape of the foundation 7 and the positions of the brackets 4 are such that the cradle can be rotated through substantially 180° about an axis defined by the pins 5. It is to be understood that the number of brackets may be varied in accordance with the length and size of the cradle 2 as desired. While I have shown the car cradle 2 of a length for handling a single car, it is to be understood that the cradle may be increased in length to accommodate a plurality of cars.

The car cradle 2 comprises a framework 8 in which a track 9 is mounted for supporting a car 10. The track 9 is carried on rollers 11 in frames 12 near the ends of the cradle

2. Guide bars 14 prevent the track 9 from assuming a position out of alignment with the axis of the cradle. Accordingly, the track 9 is adjustable within the cradle 2 for accomodating cars 10 of different widths.

Car clamps are mounted at intervals along the cradle 2. Four clamps are shown in the drawings, although it is to be understood that the number may be varied as desired. Each clamp 15 comprises a bracket 16 slidably mounted in a guideway 17 forming a part of the cradle frame. Each bracket terminates in an outwardly projecting head 18 that engages and clamps the inner edge of the car

10.

A pulley 19 is mounted in each head 18 and an outwardly extending clamping arm 20 is pivotally secured thereto. Each arm 20 terminates in a downwardly extending clamping face 21 for engaging the outer car edge. Spaced pulleys 22 and 24 are mounted near the outer end of each clamping arm 20.

A clamping cable 25 is secured to an eye 26 on the inner face of the cradle. The cable 25 extends upwardly within the bracket 16, over the top of the pulley 19, outwardly along the arm 20 and between the pulleys 22 and 24. The cable 25 selectively engages the pulleys 22 and 24 during the clamping operation hereinafter described. Each cable 25 extends over

a cooperating pulley 27 carried on a framework 28 mounted above the cradle 2. A counterweight 29 is attached to each cable 25.

During the rotation of the cradle 2 from the position shown in Figure 1 to the position shown in Figure 3, each cable 25 crosses the center line of the cooperating pulleys 19 and 27 to bring the cable into engagement with the upper surface of the pulley 22 when the cradle is in the positions shown in Figures 2 and 3.

When in this position, each cable 25 bears against the cooperating pulley 22 to force the associated clamp arm 20 into engagement with the car by reason of the counterweight 29. When the cradle is in the position shown in Figure 1, each cable 25 engages its cooperating pulley 24 for elevating the outer end of the clamp arm 20. The tension in each cable 25 also tends to move the associated bracket 16 downwardly in its guide 17.

For positively lifting the several heads 18 out of engagement with the cars 10 when the cradle 2 is in the position shown in Figure 1, each bracket 16 is provided with a flange 30 extending through a slot in the inner face of the cradle. Each flange 30 is secured to a cable 31 which extends upwardly over a pulley 32 carried by the frame 8 and downwardly exteriorly of the cradle to an eye 34 mounted on a lever 35. The lever 35 is pivotally connected to a plate 36 mounted on the foundation 7. With this construction, the lever 35 is urged in a counterclockwise direction about its pivotal support by the pressure exerted by the bracket 16 and connected parts. The bracket 16 is kept in an elevated position by reason of the engagement of a roller 36 on the outer end of the lever with a track 37 supported by a frame work 38 projecting from the body 8 of the cradle. When the cradle is in the position shown in Figure 1, the several tracks 37 engage the several rollers 36 and depress the levers 35. As the lengths of the cables 31 are fixed, the pulleys 32 are turned to raise the brackets 16 and thereby free the clamping heads 18 and clamping faces 21 from the cars 10.

As the cradle turns from the position shown in Figure 1 to that shown in Figure 2, the levers 35 follow up the tracks 37 until they reach a substantially horizontal position. During this movement, the distance between the eyes 34 and the pulleys 32 is shortened so that the brackets 16 move downwardly into engagement with the cars. The downward movement of the brackets is partially induced by their own weight and partially by the tension in the cables 25. When the cradle reaches the position shown in Figure 3, the cables 31 rest in pads 39 disposed on top of the foundation 7. In this position of the cradle the distances between the eyes 34 and the pulleys 32 is relatively short so that the several clamps 15 are drawn into firm engage-

ment with the cars 10 by the cables 25. When the cradle is returned to the position shown in Figure 1, the slack is first taken up in the cables 31, and, as the cradle nears its initial position, the rollers 36 engage the tracks 37 to depress the levers 35 which causes the brackets 16 to be raised and unclamp the car as the cradle reaches its initial position.

During the rotating movement of the cradle, the contents of the car 10 flow out of the car against a wall 40 of the cradle. The wall 40 closes the side of the cradle 2 adjacent to the brackets 4. From the wall 40 the contents of the car slide into a hopper 41 closing the upper end of the cradle and movable therewith. The movement of the contents of the car to the hopper 41 takes place slowly and without any violent falling or tumbling movement such as disintegrates the lumps of material. The hopper rotates around the pins 5 until a terminal spout 41a in the hopper is brought into close engagement with the bottom and side walls of a receiver 42, illustrated as a second car. It is to be understood that receivers of types other than cars may be utilized if desired, as the car 42 is illustrative of many types of conveying apparatus, such as transfer cars, scows, portable hoppers and the like.

When the spout 41a is in position, gates 44 closing the spout are opened and the spout is withdrawn by a slow movement, as illustrated in Figure 6, to deposit the material in the receiver by a gentle flowing movement. The action of the hopper is somewhat analogous to depositing the contents of a sack by opening the sack with an end in engagement with a support for the material to be emptied and slowly withdrawing the sack from around its contents. This operation deposits the material in the receiver without exposing the material to any injurious falling or tumbling movement down chutes or directly into the receiver.

The spout 41a is disposed substantially above the wall 40 at one side of the cradle. The plane defined by the end of the spout is at an angle to the plane of the wall 40. This angular relationship makes it possible to reach the sides of a receiver disposed near the foundation 7 and below the axis of rotation of the car cradle.

Referring to Figure 4, the gates 44 are pivotally mounted on brackets 45 carried by the spout 41a. The gates are connected by links 46 to slide rods 47, only one of which is illustrated. Each slide rod 47 is connected to a common shaft 48 through an arm 49 of a bell crank 50. An arm 51 of the bell crank is connected through a link 52 to a crank arm 54. The crank arm 54 is driven by a worm 55 meshing with teeth on the periphery of a gear 56 which also constitutes the crank arm. The worm 54 is driven by a motor 57.

As the circuit of the motor 57 may be sepa-

rately controlled, it is possible to energize the motor 57 at any desired position of the spout 41a. Upon energization of the motor the shaft 48 is rotated to slide all of the links 5 47 connected thereto longitudinally of the hopper for opening and closing the gates 44.

A rotative movement is given to the cradle 2 by drums 58 mounted on the structure 28. Preferably a drum 58 is mounted on the 10 structure 28 substantially opposite each end of the cradle. It is to be understood that the number of drums 58 may be varied in accordance with the size of the cradle.

Each drum 58 is connected by a cable 59 15 passing through a guideway 60 at the bottom of the cradle to a turnbuckle 61 connected to a post 62' at the inner side of the frame of the cradle. As the drums are wound up, the tension in the cables 59 causes the cradle 20 to turn about the pins 5 until the cable is substantially straightened out, as is shown in Figure 3. During this movement, the car clamps 15 are drawn down against the car 10 to prevent the car from moving inside 25 the cradle. A counterweight 62 is connected at each end of the cradle for returning the cradle to its upright position when the tension on the cables 59 is released. The counterweights 62 are connected by cables 64 ex- 30 tending over pulleys 65 to pins 66 positioned near the outer and upper end of each guideway 60.

While I have illustrated and described the present preferred form of my invention, it 35 is to be understood that it may be otherwise embodied within the scope of the following claims:

I claim as my invention:

1. A car dumper comprising a car cradle, 40 pivotal supporting means for the car cradle mounted at one side thereof, a car clamp within said cradle, and means for controlling said clamp, said controlling means comprising an arm pivotally mounted below said 45 pivotal support and engaging a surface of said cradle, a pulley, and a cable extending over the pulley connected to said arm and engaging the car clamp whereby as said cradle is rotated about said support, the dis- 50 tance between the center of said pulley and the free end of said arm is shortened for permitting the application of the clamp to a car and when the cradle returns to its initial position said arm is engaged by said cradle 55 for increasing the distance from the end of arm to the pulley and raising the clamp.

2. A car dumper comprising a car cradle, 60 a car clamp mounted for sliding movement in said car cradle, a pulley mounted in said car cradle at an upper edge thereof, a pivotal support for said cradle disposed along one side of said cradle near said pulley, a lever pivoted below said pivotal support and normally engaging the side of said cradle and 65 a cable connecting said lever and car clamp

over said pulley whereby as the cradle is rotated about said support the distance between the pulley and lever is shortened for permitting the car clamp to be moved into engagement with the car contained in said 70 cradle, and means for moving said car clamps independently of said lever.

3. In a car dumper, a frame, a tiltable cradle pivoted thereto, a vertically reciprocable clamp carried by the cradle for holding 75 a car thereon, a lever connected to said clamp for actuating it, said lever being pivoted to said frame eccentric with respect to the cradle pivot, so that the free end of the lever is engaged by said cradle during a portion 80 of its travel to release said clamp.

4. In a car dumper, a supporting frame, a tiltable cradle pivoted therein, said cradle having car clamps thereon, means for rendering said clamps effective when said cradle is 85 tilted, and a lever pivoted to said frame eccentric with respect to said cradle pivots so as to be engaged by the cradle when lowered, and means connecting said lever to said clamps for raising the latter. 90

In testimony whereof I have hereunto set my hand.

MILO SHUTT.
